(57) CLAIM

The ornamental design for a finger grooming wipe for pets, as shown and described.

DESCRIPTION

FIG. 1 is a front perspective view of a finger grooming wipe for pets, showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is another perspective view thereof, but shown in a usage state in an environmental view.

The broken lines illustrates environmental structure of the finger grooming wipe for pets that form no part of the claimed design.
